UNITED STATES PATENT OFFICE.

THOMAS BARTHOLOMEW, OF COLUMBUS, OHIO, ASSIGNOR TO HARRY T. HANCE, OF WESTERVILLE, OHIO.

HOOP-PROJECTING DEVICE.

1,163,609.

Specification of Letters Patent.

Patented Dec. 7, 1915.

Application filed November 26, 1913. Serial No. 803,143.

To all whom it may concern:

Be it known that I, THOMAS BARTHOLOMEW, a citizen of the United States, residing at Columbus, in the county of Franklin and State of Ohio, have invented a certain new and useful Improvement in Hoop-Projecting Devices, of which the following is a specification.

The present invention relates to the class 10 of toy illustrated in Letters Patent of the United States No. 912,059, dated February 9, 1909, and No. 935,455, dated September 28, 1909.

The object of the invention is to provide 15 a device that is easier of manufacture and more certain in operation than either of said devices and the invention consists in the construction, an example of which is shown in the accompanying drawing, set forth in the 20 following description and then pointed out in the claims.

The view of the accompanying drawing illustrates the invention in perspective.

In said view 1 designates a base of wood 25 of oblong form. Transversely of the base and through one end thereof edgewise is drilled a hole 2 and the end is sawed with a kerf as at 3 to afford access of a wire to the hole 2. The character 4 designates the 30 projector frame. This frame is made of stiff wire bent to U-form, the ends of the arms thereof being bent outward in opposite directions as indicated at 4^a. This frame is forced through the saw kerf into the hole 2, 35 said hole forming a bearing in which the frame can oscillate. Between the angles formed by the bent-out ends 4^a is stretched an ordinary rubber band 5.

The projector is operated as follows: The 40 hoop 6 of wood or other suitable material is wedged and positioned between the rubber band 5, which stretches and the base 1 substantially as shown in the view and then the wire frame drawn down toward the base

by the application of the fingers of the hand 45 to the bent-out ends 4^a. When the wire frame is drawn the arc of the hoop held between the rubber band and the base becomes less until the purchase is no longer sufficient to retain the hoop. The hoop is 50 thereupon forcibly projected and at the same time given a rotary motion by the sudden release of the rubber band from its stretched condition. Said rotary motion continues 55 after the hoop strikes the floor or ground and such motion is of a direction to cause the hoop by friction with the floor or ground to return toward the user after the force of the outward projection is spent. The base 60 can be held in one hand while the other operates the wire frame to release the hoop or said base can be placed on the floor and held when the wire frame is operated.

The device is susceptible of some modifications without departing from the gist of 65 the invention. It is not necessary, for example, that the frame 5 be made out of one piece of wire.

What I claim is:

1. A hoop projecting device comprising, 70 in combination, a base, a frame fulcrumed thereon, and an elastic member on the frame to engage the rim of the hoop.

2. A hoop projecting device comprising, 75 in combination, a base, a frame fulcrumed thereon, said frame having finger pieces for actuating the same, and an elastic member on the frame to engage the rim of the hoop.

3. In a hoop projecting device, the combination of a base, and a two armed frame 80 fulcrumed to said base to receive a flexible member extending between them, said flexible member to engage the rim of the hoop, substantially as described.

THOMAS BARTHOLOMEW.

Witnesses:

BENJAMIN FINCKEL,
CASSIUS M. BARTHOLOMEW.
